UNITED STATES PATENT OFFICE.

PAUL J. WILSON, OF GRIMES, IOWA.

DOUBLE-ACTING-PUMP-OPERATING MECHANISM.

1,328,218.

Specification of Letters Patent. Patented Jan. 13, 1920.

Application filed October 8, 1919. Serial No. 329,269.

To all whom it may concern:

Be it known that I, PAUL J. WILSON, a citizen of the United States, residing at Grimes, in the county of Polk and State of 5 Iowa, have invented certain new and useful Improvements in Double-Acting-Pump-Operating Mechanism, of which the following is a specification.

The invention relates to means for operating a double acting pump, said means being particularly designed for use in connection with a windmill, whereby the plungers of a double acting pump may be operated simultaneously in opposite directions 15 so as to insure the continuous flow of a stream of water.

The drawings illustrate a preferred embodiment of the invention. However, it is to be understood that in adapting the same 20 to meet different conditions, various changes in the form, proportion, and minor details of construction may be resorted to without departing from the nature of the invention as claimed hereinafter.

25 In the accompanying drawings;

Figure 1 is a view in elevation of a double acting pump operating mechanism embodying the invention, the dotted lines indicating the operation of the mechanism,

30 Fig. 2 is a sectional detail on the line 2—2 of Fig. 1 looking in the direction of the arrow, and

Fig. 3 is a horizontal section on the line 3—3 of Fig. 1.

35 Corresponding and like parts are referred to in the following description and indicated in the several views of the drawings by like reference characters.

The numeral 1 designates the mast of a 40 windmill and the same may be of any desired construction and arrangement. The pump rods are designated by the numerals 2 and 3, and may be connected with the windmill, not shown, and the plungers of 45 the pump, not shown, in any manner well understood in the art. The pump rods are disposed one within the other and are adapted to be simultaneously operated in reverse directions.

50 Two arms 4 are connected at their lower ends to the mast 1 and support levers 5 at their upper ends. The arms 4 and levers 5 are located upon diametrically opposite sides

of the mast. The inner ends of the levers 5 are connected to the pump rod 3 by means 55 of links 6 and a clamp 7.

Arms 8 are made fast at their inner ends to the pump rod 2 and incline outwardly and downwardly and terminate in depending forks 9 which receive the outer ends of 60 the arms 5. A pair of rollers 10 is mounted between the members of each fork 9, and the rollers are spaced apart to receive the outer ends of the levers 5. The arrangement is such that the pump rods 2 and 3 move in 65 opposite directions a like distance, hence the pump plungers are moved in reverse directions a uniform distance.

The arms 4 may be secured to the mast in any manner and as shown most clearly in 70 Fig. 3, their lower ends are bent so as to embrace the mast, one bent end passing through the companion arm and being threaded to receive a clamp nut 11, by means of which the clamp elements may be drawn 75 about the mast so as to engage the same by a binding action and hold the arms 4 in the located position. The outer ends of the arms 5 terminate in cross-heads 12 which form stops to prevent the outer ends of the 80 arms from being drawn through the forks 9.

Having thus fully described my invention, what I claim as new and desire to secure by Letters Patent is:—

1. In operating mechanism for a double 85 acting pump, and in combination with two pump rods, opposing levers pivotally supported intermediate their ends, links connecting one of the pump rods with corresponding ends of the levers, and arms extending from the other pump rod and having sliding connection with opposite ends of the levers.

2. In operating mechanism for a double acting pump embodying a mast and two 95 pump rods, opposed arms rigidly connected to the mast, levers mounted intermediate of their ends on the arms, links connecting the inner ends of the lever with one of the pump rods, and arms rigidly connected to 100 the other pump rod and having sliding connection with the other end of the said levers.

3. In a double acting pump embodying a mast and two pump rods, oppositely disposed arms having their lower ends bent 105 laterally to form clamp elements which em-

brace and secure the arms to the mast, oppositely disposed levers pivoted intermediate of their ends to the arms, links connecting the inner ends of the levers to one of the pump rods, oppositely disposed arms secured to the other pump rod and terminating in forks which receive the outer ends of the said levers and a pair of rollers mounted

in each fork to receive the outer ends of the coöperating lever.

In testimony whereof I affix my signature in presence of two witnesses.

PAUL J. WILSON.
